UNITED STATES PATENT OFFICE

ERNEST JAMES SMITH, OF LONDON, ENGLAND, ASSIGNOR TO THE GOSS PRINTING PRESS COMPANY, OF CHICAGO, ILLINOIS, A CORPORATION OF ILLINOIS

PRINTING PRESS

Application filed July 7, 1928, Serial No. 290,907, and in Great Britain January 13, 1928. Renewed
March 3, 1932.

This invention relates to printing presses, the chief object being to provide improved means for enabling the leading end of the web from a new or reserve paper supply roll to be joined to the active web of the exhausting paper supply roll without the use of separate or additional pressure rollers such as have hitherto been proposed for effecting the joining of the two webs.

10 According to this invention means are provided for effecting contact between the new or reserve paper supply roll and the exhausting paper supply roll to cause the two paper webs to be pressed together between the said rolls so that by means of adhesive previously applied say to the reserve web, the latter can be joined or united to the active web and drawn by the latter into the press, whereupon the active web can be cut or severed from its reel or core to enable the supply to be drawn from the new or reserve roll. Each of the said supply rolls may be carried on an angularly movable support such as a pair of angularly movable members or arms mounted on a shaft or the like and either pair of the said members or arms can be moved for example by partially rotating the shaft on which they are mounted by means of suitable gearing for lifting the supply roll carried by the said members or arms and for causing it to be pressed against the other supply roll supported in the other pair of members or arms so as to enable the two webs to be pressed together and united as aforesaid. The supply rolls are rotatably supported by the said arms in any appropriate manner and in one construction each pair of the supporting arms may carry rotatable spindles having bungs or the like on their inner ends for engaging with the ends of the reel or core within the paper supply roll to support the latter. One (or both) of the bung spindles of each pair may be axially movable for enabling it to be moved into and out of engagement with the said reel or core. Angular movement may be imparted to either pair of the supporting arms by means of worm gearing which may be operated by hand or otherwise and in one example a worm wheel sector is mounted on

each of the shafts carrying the said supporting arms and is adapted to be engaged by a worm on an operating spindle. The operating spindles pertaining to the two sets of worm gearing may be so disposed that either can be engaged by a common operating device according to whichever of the two spindles is to be actuated. For the purpose of controlling the speed of rotation of each paper supply roll, braking means may be associated with the aforesaid bung spindles which means may comprise a friction band or gripping device around a part on or of one spindle of each pair and adapted to be actuated by hand or by automatic means which latter may operate according to the tension on the web as the latter travels from either supply roll into the press.

In order that the said invention may be clearly understood and readily carried into effect, the same will now be described more fully with reference to the accompanying diagrammatic drawings, in which:—

Figure 1 is a side or end view showing one construction of the improved mechanism as seen from one side of a printing press.

Figure 2 is a transverse view showing one of the paper supply rolls in its supporting arms and the actuating mechanism for moving the said arms.

Figure 3 is a plan view of the parts shown in Figure 2.

Figure 4 is a transverse view illustrating (on a larger scale) one pair of supporting arms on their operating shaft, one of the arms being shown in section at its upper part.

Figure 5 is a plan view of one form of side lay adjusting device.

Figure 6 is a detail view of the hand operating braking mechanism.

Figures 7 and 8 are respectively a side or end view and a fragmentary transverse view showing one construction of automatic braking mechanism.

1 represents one of the paper supply rolls, which as shown in Figure 1 may be the active roll approaching exhaustion and 2 indicates the other paper supply roll, which may be regarded as the new or reserve roll. Each paper supply roll is carried or supported by

55

100

a pair of angularly movable arms 3 secured on a transverse shaft 4 rotatably mounted in the side frames or members 5 of the printing press. In the example shown, each of the supporting arms 3 receives at its upper end a short spindle 6, the said spindles of each pair of arms 3 being in alignment and provided at their inner ends with bungs 7 that are adapted to be fitted in the ends of the reel or core 8 on which the paper web is mounted to form the supply roll. The said bung spindles 6 may be splined in sleeves or bushes 9 rotatably mounted in roller or other bearings 10 in the upper ends of the said arms. The spindle in 15 one of the aforesaid arms is held against axial movement and it is provided with a thrust bearing 11 but the other spindle is adapted to be axially moved within its sleeve 9 so that the bung 7 on the inner end thereof can be moved into engagement with one end of the reel or core when the paper supply roll is in position with the other end of its reel or core engaged by the bung on the spindle having the said thrust bearing 11. In the example 20 shown the outer end of the axially movable spindle is provided with a grooved collar 12 with which engage pins 13 on a lever 14 whose lower end is loosely connected to the supporting arm 3 by a link 15 whilst its upper end carries a swivel sleeve 16 or the like in which is mounted a screw threaded rod 17 that is screwed into a threaded socket 18 on the aforesaid arm 3. By rotating the said rod 17, for example by a hand wheel 19 the lever 25 14 can be displaced so that its pins 13 engaging with the collar 12 on the axially movable spindle, cause the latter to be moved inwardly for enabling its bung to engage with the reel or core 8 of the paper supply roll or to be moved outwardly for withdrawing the said bung from the reel or core. On the transverse shaft 4 pertaining to each pair of supporting arms 3 is keyed or otherwise secured a worm wheel sector 20 which is engaged by a worm 30 21 mounted on a spindle 22 in suitable bearings 23 in a fixed part 5a secured to the frame 5, the said worm spindles 22 pertaining to the two shafts 4, being in co-axial alignment. The inner ends of the said spindles 22 are provided with bevel pinions 24 and located between these pinions is a bevel gear wheel 25 which is carried on a lever 26 pivoted at a position between its ends to the fixed frame 5a the upper end of the said lever being adapted 40 to be secured to the fixed frame by means of a detachable pin 26a in either of two positions. When the pin 26a is removed, the aforesaid lever 26 can be moved to place the bevel gear wheel 25 into engagement with either of the aforesaid bevel pinions 24 and when it is so engaged it may be locked in engagement by inserting the pin 26a in the end of the lever 26 into a hole in the fixed frame 5a thus securing the lever to the said frame as aforesaid. The bevel gear wheel 25 may then be

rotated by hand or otherwise and in the example shown its spindle or shaft 27 is adapted to receive a detachable handle 28 so that it can be rotated by hand for the purpose of rotating the aforesaid worm 21 and imparting angular movement to the worm sector 20, the shaft 4 and the supporting arms 3. During the supply of the web into the press from the active roll 1 which initially is of the size shown in dotted lines 1a in Figure 1 and becomes reduced to the size shown at 1 in full lines when approaching exhaustion the new or reserve paper supply roll may be wheeled into the press on a truck or the like into a position in which it can be disposed or rolled between the arms 3 that are to support it. The arms 3 are then angularly moved to place the bungs 7 in proximity to the ends of the reel or core of the supply roll and whilst one end of the reel or core is held against the bung having the thrust bearing 11 the axially movable bung may be caused to engage with the other end of the reel or core so that the supply roll is securely held on the rotatable spindles 6 in the supporting arms 3. After the reel or core of the said supply roll has been engaged by or gripped between the bungs 7 the roll can be lifted into its operative position by raising the supporting arms 3 which are moved as a result of rotating the handle 28 and operating the worm 21 and the worm sector 20 pertaining thereto. Adhesive may be applied at or near the leading edge of the web thereon of the new or reserve supply roll and the operator can rotate this roll by hand so as to bring the part bearing the adhesive into position for enabling the active and exhausting web when pressed against the reserve roll to be joined to the leading end of the reserve web. The lever 26 carrying the aforesaid bevel gear wheel 25 may now be moved to place the latter in engagement with the bevel pinion 24 of the worm gearing pertaining to the arms 3 carrying the active and exhausting roll 1 and by rotating the aforesaid handle 28 the bevel gearing and the worm gearing is operated to move the supporting arms carrying the active and exhausting roll 1 so as to press this roll whilst rotating against the aforesaid new or reserve roll which has been placed in the operative position as aforesaid, so that the active web becomes united to the reserve web by the adhesive in the latter. The active and exhausting supply roll may bear against the other supply roll with resilient or yielding pressure to allow for any unevenness and for this purpose each worm 21 may be so mounted on its operating spindle 22 that it can be moved against the action of a spring 29 when either roll is being pressed against the other but it can be locked against such movement by means of a pivoted slip collar 30 that can be placed on the operating spindle to engage with a shoulder 31 thereon and thus retain 130

- the spindle against the endwise movement as is desirable for example when raising the supply roll into the operative position. After the web from the reserve roll has been united 5 to the active and exhausting web and is being drawn into the press and after the active web has been cut or severed from its reel or core, the reserve roll becomes the active roll and after removing the reel or core of the exhausted roll from the supporting arms 3 a new or reserve roll can be placed between these arms so as to be secured thereto by the bungs as aforesaid ready for the next web joining operation.
- 10 For the purpose of side lay adjustment each transverse shaft 4 carrying the said supporting arms 3 for the supply roll may be threaded at one end onto a rod 32 (or into a sleeve or bush) which is rotatably mounted in a fixed bar 33 and provided with a hand wheel 34 that can be rotated to impart endwise movement to the said shaft 4 and thus adjust the lateral position of the supporting arms as required.
- 15 One of the two bung spindles pertaining to each supply roll may be provided with a brake for controlling the speed of rotation of the supply roll as the web is drawn therefrom into the press and the brake may comprise 20 a split friction ring 35 or the like which is located between the aforesaid roller bearings 10 around an enlarged part of the sleeve or bush 9 containing the bung spindle 6 and is adapted to be controlled or regulated 25 by a hand screw 36 (see Figures 4 and 6).
- The automatic braking mechanism shown 30 in Figures 7 and 8 is located at one side of the press and is operated according to the tension on the active web as it passes into the press 35 from whichever of the two supply rolls is at that time serving as the active roll. The web from either supply roll passes around a spring influenced roller 37 and also around other rollers 38 and 39 as shown in Figure 7.
- 40 The roller 38 is slidably mounted in a guide 40 and is connected by a link 41 to one end of the bell crank lever 42 whose other end is connected to a link 43 that extends downwardly and is pivotally attached to a lever 44 on a shaft 45 carrying a pulley or wheel 46 around or to which two cables 47, 47 are secured. The bell crank lever 42 is carried 45 on shaft 42b on which shaft is rotatably mounted a worm wheel 55 that is engaged by a worm 56 and is connected to a torsion spring 42a (see Figure 8) located around a shaft 42b so that movement of the roller 38 in its guide 40 due to the tension on the web is effected against the torsional action of this 50 spring. Each of these cables passes around a jockey pulley 48 on an arm 49 angularly movable on the aforesaid shaft 45 whence it passes around a pulley 50 on the transverse shaft 4 having the supporting arms 3 that carry the paper supply roll. The outer extremity 55 of each cable is connected to a bell crank lever 51 that is attached to a brake band 52 surrounding the sleeve 9 in which the bung spindle 6 is splined as aforesaid. The said brake band 52 is adapted to be contracted or released by movement of the bell crank lever 51 due to the operation of the aforesaid link and lever mechanism 41, 42 and 43 according to the tension on the web passing into the press. The outer end of each of the arms 49 is slotted 60 to provide a sliding connection for one end of a link 53 whose other end is pivotally attached to a collar 54 or other part fixed on and movable with the transverse shaft 4 and the supporting arms 3. As the tension on the web passing into the press increases, the roller 38 is slidably moved in its guide 40 in a direction that causes the link 41 to move the bell crank lever 42 against the action of the torsion spring 42a for raising the link 43 and imparting angular movement to the shaft 45 and the pulley 46 with the result that the cables 47 are slackened, thus enabling the brake band 52 to be released to allow the active supply 65 roll to rotate at a higher speed. When the tension on the web decreases, the roller 38 slidably moves in its guide 40 in the opposite direction due to the aforesaid torsion spring 42a with the result that the link and lever mechanism 41, 42 and 43 is moved in the 70 direction opposite to that aforesaid so that the shaft 45 and pulley 46 are angularly moved for causing the cables to be wound further around the pulley 46 in order to actuate the bell crank lever 51 for contracting the 75 brake band around the sleeve 9 in which the bung spindle 6 is splined, thus retarding the speed of rotation of the paper supply roll from which the web is being drawn. Each 80 of the aforesaid arms 49 serves as a compensating device for taking up any slack in the cable 47 when the paper supply roll supporting arms 3 are angularly moved, by reason of the aforesaid link 53 connected to the collar 54 which move with the said arms 3, angularly displacing the lever 49 so as to change the position of the jockey pulley 48 thus enabling the cable to be maintained taut for any angular position of the said supporting arms 85 so that they can be operated by the aforesaid link and lever mechanism 41, 42 and 43 according to the tension on the web as hereinbefore described irrespective of the angular position of the supporting arms carrying the paper supply roll. The torsional effect of the spring 42a can be varied according to requirements and for this purpose the worm wheel 55 which is movable with the bell crank lever 42 and is connected to the said spring 90 can be rotated by the worm 56 whose spindle is provided with an operating hand wheel 56a as shown in Figure 7. Each brake band 52 may be operated by hand if desired for which purpose a hand screw 57 may be mounted 95 so as to be connected to the bell crank lever 100

51 (as shown in Figure 7) for enabling the latter to contract or release the brake band when the hand screw 55 is rotated.

Obviously, the mechanism shown in Figs. 5 1-3 for turning the shafts 4 may be used for turning the shafts 4 of Figs. 7 and 8.

What I claim and desire to secure by Letters Patent of the United States is:—

1. Web roll supporting mechanism including in combination two pairs of angularly movable supporting members for carrying a pair of web rolls, means for moving the web rolls into contact with each other to join an expiring web with the reserve web roll, and means for resiliently pressing the running web into contact with the reserve web roll.

2. Web roll supporting mechanism including in combination angularly movable supporting members for carrying a pair of web rolls, worm gears connected with the supporting members, worms for moving the gears and web roll supporting members, and springs cooperating with the worms to provide a yielding contact between the two web rolls as they are moved into contact with each other to join the running web with the reserve web roll.

3. Web roll supporting mechanism including in combination angularly movable supporting members for carrying a pair of web rolls, worm gears connected with the supporting members, worms for moving the gears and web roll supporting members, springs cooperating with the worms to provide a yielding contact between the two web rolls as they are moved into contact with each other to join the running web with the reserve web roll, and means for rendering said springs inoperative.

4. Web roll supporting mechanism including in combination relatively movable means for rotatably supporting a pair of web rolls from one of which a running web is fed to a printing press, means for moving one of the rolls into contact with the other while joining the running web to the other web roll and means for resiliently pressing the expiring web roll against said other web roll.

5. Web roll supporting mechanism including in combination relatively movable means for rotatably supporting a pair of web rolls from one of which a running web is fed to a printing press, means for moving one of the rolls into contact with the other while joining the running web to the other web roll, means for resiliently pressing the expiring web roll against said other web roll and means for tensioning the web during bodily movement of the web roll.

6. Web roll supporting mechanism including in combination relatively movable means for rotatably supporting a pair of web rolls from one of which a running web is fed to a printing press, means for moving one of

the rolls into contact with the other while joining the running web to the other web roll, means for resiliently pressing the expiring web roll against said other web roll and means for maintaining constant the web tension during bodily movement of the web roll. 70

7. Web roll supporting mechanism including in combination relatively movable means for rotatably supporting a pair of web rolls 75 from one of which a running web is fed to a printing press, means for moving one of the rolls into contact with the other while joining the running web to the other web roll, means for resiliently pressing the expiring web roll against said other web roll, a pilot roller, braking mechanism operating on the active web roll and means for connecting the roller and brake in all positions of the roll.

8. Web roll supporting mechanism including in combination relatively movable means for rotatably supporting a pair of web rolls from one of which a running web is fed to a printing press, means for moving one of the rolls into contact with the other while joining the running web to the other web roll, means for resiliently pressing the expiring web roll against said other web roll, a pilot roller, braking mechanism operating on the active web roll and flexible means connecting the roller and brake in all positions of the roll and including compensating means permitting bodily movement of the active roll without change in the web tension. 90
